(57) **CLAIM**

The ornamental design for a fish stringer, as shown and described.

DESCRIPTION

FIG. 1 is a front elevation view of the fish stringer showing my new design in use;

FIG. 2 is another front elevation view, with the rear elevation view being a mirror image thereof;

FIG. 3 is another front elevation view thereof, shown in use; and,

FIG. 4 is another front elevation view, shown in use with fish attached to the stringer.

The broken lines depict environmental structure that form no part of the claimed design.
